DIVIDING AND AMPLIFIER CIRCUIT FOR
ELECTRONIC ORGANSFrancis M. Schmidt, North Tonawanda, N. Y.,
assignor to The Rudolph Wurlitzer Company,
North Tonawanda, N. Y., a corporation of Ohio

Application January 8, 1948, Serial No. 1,115

15 Claims. (Cl. 84—1.21)

1 This invention relates to dividing and amplifier circuits for electrical musical instruments, and concerns particularly the speaker control circuits for electronic organs.

In the operation of electrical musical instruments, and specifically electronic organs of the type to which the present invention particularly relates, there is provided a plurality of banks of tone generators which are selectively operable to generate tones in the form of electrical waves, the waves being combined, amplified, and transmitted to speaking apparatus wherein they are transformed and emitted as sound. In such instruments it is frequently desirable to provide a plurality of sound emitting devices, such as loud speakers, disposed at various preselected locations in respect to the room or other chamber within which the instrument is to be played. Furthermore, it is desirable that the amplification of the generated tones be effected in a plurality of stages, the initial amplifier stages effecting the tone shaping, and the final stages being more directly associated with the speakers and facilitating the proper operation thereof. The present invention concerns more directly the division of the generated tones, after partial amplification and shaping, and the further amplification thereof and emission as sound within the speaker devices.

It is an object of the present invention to provide an improved dividing and amplifier circuit for electrical musical instruments, and particularly for electronic organs of the type defined.

More specifically stated, it is one of the objects of the present invention to provide an improved dividing network for electronic organs, wherein a plurality of speaker devices either proximately or remotely disposed may be interconnected with a single tone generating source, with a minimum of interference and maximum facility, and by means of improved switching structures.

A further object of the invention is to provide in a tone generating and reproducing system of the type defined, improved tone or electrical impulse dividing and amplifying means, effective to preserve the wave shape of the oscillations or pulsations delivered thereto, and operable to insure proper speaker operation over a wide range of frequencies without undesired speaker intermodulation.

Various other objects, advantages and features of the invention will be apparent from the following specification when taken in connection with the accompanying drawings, wherein a preferred

2 embodiment is set forth for purposes of illustration.

In the drawings, wherein like reference numerals refer to like parts throughout:

5 Fig. 1 is a diagrammatic view of an electrical musical instrument, and specifically an electronic organ, incorporating a tone producing, dividing, and amplifier circuit constructed in accordance with and embodying the principles of the invention;

Fig. 2 is an electrical schematic diagram of the system;

Fig. 3 is an electrical diagram and schematic view, more particularly showing one of the tone cabinet amplifiers; and

Fig. 4 is a detail view showing a part of the tone generators.

The particular electronic organ illustrated in Fig. 1 comprises a console casing or housing **10** arranged to support a "Great" manual or keyboard **12**, a "Swell" manual or keyboard **14**, and a "Pedal" clavier **16**. There is also provided a volume control pedal **18**, by means of which the over-all volume or level of the instrument may be controlled, and a series of stop tablets **20** by means of which the various tone generators are caused to be activated and the volume thereof controlled, in banks, in the particular instrument shown.

30 Further disposed within the console casing **10** is a plurality of banks of tone generators **22** which may, for example, be of the type and kind shown in the patent to Hoschke No. 2,015,014. More specifically, and as shown in Fig. 4, these tone generators comprise a series of vibratory reeds **24** individually disposed within cells **26**, each reed having associated therewith an adjustable pickup screw **28** forming with its associated reed a capacitor variable in accordance with the reed vibrations. Air is admitted to the cells **26**, so as to cause the selective vibration of the reeds, by means of a series of pallet valves **30**, the selective operation of which is controlled conjointly by the keys of the manuals, and those of the pedal clavier, as determined by the operation of the stops **20**. This control is effected by coupler boards as shown at **32** and **34**, the coupler boards containing switches selectively actuated by the keys of the manuals and pedal clavier, in accordance with the selected stops which have been depressed, so as to cause the operation of the desired pallet valves to thereby admit actuating air to vibrate the desired reeds. The air supply for the reeds is provided from a blower **36**.

The electrical output from the tone generators

or reeds is transmitted to a first stage amplifier 38 within the console, the volume control mechanism 40 operated by the swell pedal 18 being associated with said amplifier 38, so as to effect the volume control of the instrument.

The stops 20 not only select the pallet valves for operation, but also control the intensity of various of the reed banks, the stop controlled intensity switches being illustrated at 42, 44 and 46 in Fig. 2.

Remotely disposed in respect to the organ console, and connected thereto by a cable 48, Fig. 1, is a series of tone outlets, which in the specific embodiment illustrated in Fig. 1 comprises a pair of main tone cabinets 50 and 52, and an echo tone cabinet 54. The details of the mechanisms disposed in the tone cabinets, and the connections therefor, form a part of the present invention and will hereinafter be more specifically described.

Referring to the schematic wiring diagram, Fig. 2, it will be seen that there is provided a rectifier unit 56, which may preferably be of the full wave electronic tube type, powered from a suitable source of A. C. supply as indicated at 58. The negative D. C. line 60 from the rectifier is connected to ground through a resistor 62, whereas the positive D. C. wire 64 leads to a bank of celeste reeds 66 through a resistor 68 and wire 69, and to a bank of diapason reeds 70 through a resistor 72, as shown.

The D. C. supply line 64 is further connected by means of a variable resistor 74 with a bank of viole reeds 76, and by means of a variable resistor 78 with a bank of pedal reeds 80, and by means of a variable resistor 82 to a bank of flute reeds 84.

A predetermined greater voltage may be applied to the viole reeds through a resistor 86 by the closing of stop switch 46, and to the pedal reeds through a resistor 88 by the closing of stop switch 44, and to the flute reeds through a resistor 90 by the closing of the stop actuated switch 42.

As best shown in Fig. 4, wherein a group of the celeste reeds is specifically shown, the reeds are connected in parallel to their polarizing voltage supply source, and to ground through a suitable resistor as indicated at 92.

By means of the described connections polarizing voltages of predetermined selective intensity may be variably applied to the reed banks. These connections are more specifically set forth in my copending applications, Serial No. 1,112 and Serial No. 1,113, filed of even date herewith, to which reference may be made, if desired.

As also best shown in Fig. 4, it will be seen that the tone screws or pickups 28 are connected in parallel to an output wire as indicated at 94 in the case of the celeste reeds, this wire leading to the preamplifier 38. Similarly the tone screws of the remaining reed banks are connected to the preamplifier by suitable connections as indicated at 96, 98 and 100. The signal circuit to the preamplifier further includes a capacitor as indicated at 102, in by-pass relation to each of the resistors 92.

As more particularly pointed out in said Hoschke patent, the reed vibrations produce electrical oscillations or pulsations transmitted to the amplifier, the intensity of which is controlled by the magnitude of the polarizing voltages. The tone quality of each reed bank is different, as indicated by the name designations applied thereto, such quality differences or dif-

ferences in generated wave shape being due, in part, to control of the physical relationships in the tone screw-reed capacitors.

As more particularly pointed out in my U. S. Patent No. 2,555,295, granted May 29, 1951, wherein the details of the preamplifier 38 are particularly set forth, the wave shapes generated by the reed vibrations are further controlled, preserved, or modified within the preamplifier structure by various wave shaping components, whereby the output tones or waves from the preamplifier will have the desired shape or quality, and proper harmonics, throughout the full frequency and intensity range of the instrument. The present invention concerns the means and methods by which the output tones, or more accurately stated the output electrical oscillations from the preamplifier 38, are further amplified and their wave shape preserved, and transmitted to the several desired tone outlets.

As more particularly pointed out in said copending application, Serial No. 1,114, the preamplifier 38 comprises a plurality of amplifier stages, the final Class A power tube of which feeds a transformer herein illustrated in Fig. 2 at 104, having a primary 106 and a secondary 108.

Referring further to Fig. 2, and in accordance with the present invention, it will be seen that one end of the transformer secondary is connected directly to ground by means of a line 110, whereas the other end of the secondary is connected to ground through a line 111 and a pair of series-connected resistors 112 and 114 forming a voltage divider. A pair of resistors 116 and 118 forming a second voltage divider is connected to ground in parallel with the resistors 112 and 114, as shown. A variable tap connection 120 leads from the resistor 114 by means of a line 122 to the echo tone cabinet 54, whereas a variable tap 124 connects with resistor 118 and leads by means of lines 126 and 128, respectively, to the main tone cabinets 50 and 52. A suitable source of A. C. power supply, as indicated at 130, is also interconnected with the several tone cabinets, as shown, the wire connections to the tone cabinets being effected through socket plugs 132, 134 and 136. By way of illustration, the A. C. supply wires to the tone cabinet 50 are indicated by the reference numerals 138 and 140.

A line 142 interconnects the midpoint between resistors 112 and 114 with a normally closed switch 144 adapted to be opened by the depression of a manually operable stop tablet 146. Switch 144 is series-connected to ground through the normally closed contacts 148a of a second switch structure 148, arranged for operation by a second manually operable stop member, as shown at 150. The normally opened contacts 148b of this latter switch are interconnected by means of a line 152 with the midpoint between resistors 116 and 118. Depression of the stop 150 opens switch contacts 148a and closes contacts 148b.

When the switches 144 and 148 are in the position illustrated in Fig. 2, line 142 shorts the resistor 114 so that the echo tone cabinet 54 is inoperative; whereas line 152 is in open circuit condition so that resistor 118 is operative to transmit a predetermined fraction of the signal output from the preamplifier to the tone cabinets 50 and 52. The fraction thus transmitted to the main tone cabinets 50 and 52 is determined by the proportioned resistance values of

the resistors 112—118, as well as by the position of the adjustable tap 124.

Depression of stop 143 opens switch 144, thus throwing short circuit line 142 into opened circuit condition and thus rendering resistor 114 operative to transmit a predetermined fraction of a signal through adjustable tap 120 to the echo tone cabinet 54. Under such conditions, all tone cabinets will be operative. Depression of stop 150, while stop 146 remains undepressed, effects an opening of contacts 148a to render the echo tone operative, and a closing of contacts 148b to render the main tone cabinets 50 and 52 inoperative, so that only the echo tone cabinet will be heard.

The connections thus provided form a simple switching arrangement for selectively energizing the main and echo tone cabinets. The connections furthermore provide ready means by which the signal fraction to be transmitted to the several tone cabinets may be adjusted for volume intensity control, as desired; and, still further, the arrangement of the parallel resistors is such that a minimum disturbance will result in the operation of one tone cabinet when another is rendered selectively operative or inoperative. If additional tone cabinets are added to the system, suitable compensating adjustments may be readily made by the taps 120 and 124. The operation of the stops 146 and 150 merely controls the disabling of short circuits and thus a minimum of shock is transmitted to the tone cabinet circuit as the stop switches are selectively actuated.

Referring further to Fig. 2, it will be seen that each main tone cabinet includes a divider 154 and a pair of amplifiers 156 and 158, supplied thereby, each amplifier being provided with a pair of speakers, as indicated at 160. The echo tone cabinet may be similarly constituted or, as shown in Fig. 2, may comprise an amplifier 162 feeding to a divider 164 which, in turn, supplies a pair of loud speakers, as indicated at 166. The dividers and amplifiers may be similarly constituted. The specific construction for the tone cabinet 50 is set forth in Fig. 3.

Referring to Fig. 3, it will be seen that the junction and divider unit 154 comprises a low pass filter 168 and a high pass filter 170. More specifically, the low pass filter comprises a wire 172 interconnecting with the signal or tone supply wire 126, and leading to an isolating resistor 174. This resistor interconnects with a series choke 176 and a capacitor 178 to ground, forming a first filter section. The low pass filter further comprises a series resistor 180 and a ground connected capacitor 182, forming a second filter section, and a terminating or load resistance to ground, as indicated at 184. Wire 186 interconnects the low pass filter with the low frequency amplifier 158 feeding a pair of loud speakers 160, as previously described. The amplifier 158 is preferably of identical structure with the high frequency amplifier 156, presently to be described.

The high pass filter 170 comprises a line 188 interconnecting with the signal supply, which line leads to an isolating resistor 190. The filter further comprises a pair of series-connected capacitors 192, a ground connected choke 194, and a terminating resistance to ground in the form of a voltage divider comprised of four resistor sections, as indicated at 196, 198, 200 and 202. An adjustable tap switch 204 is arranged so that any one of several fractions of the volt-

age divider may be tapped off and transmitted to a line 206 leading to the high frequency amplifier. The adjustment 204 insures a proper proportioning of the low and high frequency intensities to accord with the acoustics of the installation wherein the tone cabinet is to be located.

5 The amplifier 156 comprises a full-wave tube rectifier 208 powered from the A. C. supply wires 138 and 140. The positive or B+ D. C. supply line from the rectifier is indicated at 210 and the negative return line at 212.

10 The signal circuit wire 206 from the high pass filter connects through a safety coupling capacitor 214 to the grid of a voltage amplifier triode 216, there being a grid load resistor 218 connected to ground as shown. The cathode bias circuit for the tube 216 comprises a resistor 220 and a resistor 222 in series, forming a voltage divider, the resistor 220 being by-passed by a 15 capacitor as indicated at 224.

15 The plate circuit for the tube 216 comprises a load resistor 226 interconnected with the B+ voltage supply line 210 from the rectifier through a pair of voltage dropping and isolating resistors 228 and 230. The B+ supply line further includes a series of filter capacitors to ground as indicated at 232, 234 and 236.

20 The load circuit of amplifier tube 216 is connected by means of a coupling capacitor 238 with the grid of a no-gain, phase inverter triode 240 which for convenience may be disposed in a common envelope with the amplifier 216, forming a dual triode structure.

25 The grid load resistor circuit for the phase inverter tube comprises a pair of resistors in series as indicated at 242 and 244, the latter resistor also being in series connection with a resistor 246 in the cathode circuit of the phase inverter tube, the resistor 246 being by-passed by a 30 capacitor as indicated at 248.

35 The plate circuit for the phase inverter tube comprises a load resistor 250 connected to the B+ source of supply, said load circuit being connected by means of a coupling capacitor 252 with the control grid of a pentode tube 254, said tube together with a similar pentode tube 256 forming a Class A push-pull amplifier stage.

40 The cathode bias circuit for the push-pull tubes comprises a resistor 258 by-passed by a capacitor as indicated at 260. The grid load resistors for the push-pull stage are indicated respectively at 262 and 264, the latter being coupled to the cathode circuit of the phase inverter tube through a coupling capacitor 266.

45 The resistors 260 and 244 are preferably of equal value, and similarly the resistors 262 and 264 are of similar value. The plate resistor 250 constitutes a load for resistor 262, whereas the cathode resistor 244 constitutes an opposed phase 50 load resistor for the resistor 264 in a cathode follower circuit. The plate and cathode resistors of the phase inverter tube thus drive the push-pull stage, as will be understood. Resistor 230 constitutes a grid dropping resistor for the screen 55 grids of the push-pull tubes through wire connection 268, as shown.

60 The plates of the push-pull tubes are connected to the opposite ends of the primary coil 270 of the speaker load transformer, the primary coil being center tap connected to the B+ source of supply; and there being a phase correcting or stabilizing circuit comprising a capacitor 272 and a resistor 274 interconnected between the tube plates as shown.

65 The secondary coil 276 of the load transformer

is series connected to the voice coils 278 and 280 of the speakers, the transformer secondary also being center tap connected by means of a line 282 and a resistor 284 to the cathode circuit of amplifier tube 216, forming an inverse feed back circuit.

The field coil 286 of one of the speakers is interconnected with the B+ D. C. supply source by means of a wire 288, resistor 230 forming a dropping resistor for the voltage supplied. The field coil 290 of the other speaker is interconnected with the B+ source of supply through a line 292 and a similar voltage dropping resistor 294. A switch 296 may be opened to disable the second speaker, and when opened causes a normally shorted resistor 298 to be inserted into the return line 300 of the first speaker field coil whereby to maintain the voltage drop therein substantially constant.

The amplifier circuit above described, comprising the amplifier 156, is characterized by a substantially flat or straight line amplification characteristic over a wide frequency band. The combination of such type amplifier with the high and low pass filter circuits, as described, produces a composite straight line amplifier throughout a wide frequency range in the tone cabinets for cooperation with the preamplifier 38, preserving the wave shape imparted to the generated tones in the preamplifier, and producing a minimum of intermodulation between the speakers throughout the volume and frequency range of the instrument. As will be understood, due to the action of the high and low pass filters, the amplifier 156 is provided essentially for high frequency amplification and the amplifier 158 essentially for amplification of low frequencies, in the operation of the structure.

It is obvious that various changes may be made in the specific embodiment set forth for purposes of illustration without departing from the spirit of the invention. The invention is accordingly not to be limited to the specific embodiment shown and described, but only as indicated in the following claims.

The invention is hereby claimed as follows:

1. An electronic musical instrument comprising a plurality of tone generators, means for combining the output from said generators to form a single composite signal, a plurality of tone outlets, and means for selectively transmitting said composite signal to said plurality of outlets comprising a signal circuit, a plurality of resistors disposed substantially in parallel with one another and arranged for connection in said circuit, means for selectively rendering said resistors operative and inoperative, and amplifying means interconnecting said resistors with said tone outlets.

2. An electronic musical instrument comprising a plurality of tone generators, means for combining the output from said generators to form a single composite signal, a plurality of tone outlets, and means for selectively transmitting said composite signal to said plurality of outlets comprising a signal circuit, a plurality of resistors disposed substantially in parallel with one another and arranged for connection in said circuit, means for selectively rendering said resistors operative, an amplifying channel connected to each tone outlet, and adjustable tap means interconnecting said resistors with said tone outlets through the amplifying channels.

3. An electronic musical instrument compris-

ing a plurality of tone generators, means for combining the output from said generators to form a single composite signal, a plurality of tone outlets, and means for selectively transmitting said composite signal to said plurality of outlets comprising a signal circuit, a plurality of resistors connected substantially in parallel with one another to said circuit, means for selectively short circuiting said resistors, and a plurality of amplifying means each interconnecting one of said resistors with one of said tone outlets.

4. An electronic musical instrument comprising a plurality of tone generators, means for combining the output from said generators to form a single composite signal, a plurality of tone outlets, and means for selectively transmitting said composite signal to said plurality of outlets comprising a signal circuit, a plurality of sets of series-connected resistors arranged for connection substantially in parallel with one another in said circuit, each set of resistors forming a voltage divider, means for rendering the terminal resistor of each set selectively operative

20 or inoperative, and a plurality of amplifying means each interconnecting one of said terminal resistors with one of said tone outlets.

5. An electronic musical instrument comprising a plurality of tone generators, means for

30 combining the output from said generators to form a single composite signal, a plurality of tone outlets, and means for selectively transmitting said composite signal to said plurality of outlets comprising a signal circuit, a plurality of sets of series-connected resistors arranged for connection substantially in parallel with one another in said circuit, each set of resistors forming a voltage divider, means for rendering the terminal resistor or each set selectively operative

35 or inoperative, and a plurality of amplifying channels and means comprising a series of adjustable taps interconnecting said terminal resistors with said tone outlets through said plurality of amplifying channels.

6. An electronic musical instrument comprising a plurality of tone generators, means for

40 combining the output from said generators to form a single composite signal, a plurality of tone outlets, and means for selectively transmitting said composite signal to said plurality of outlets comprising a signal circuit, a plurality of resistors permanently connected substantially in parallel with one another in said circuit, means comprising a pair of manually operable stop switches for selectively rendering said resistors operative, and means interconnecting said resistors with said tone outlets.

7. An electronic musical instrument comprising a plurality of tone generators, means for

50 combining the output from said generators to form a single composite signal, a tone outlet including a plurality of speakers, and means for transmitting said composite signal to the speakers comprising an amplifier, a high pass filter, a low pass filter, means for rendering at least one of said speakers inoperative, and means respectively connecting said speakers to said filters, to give a broad frequency range output.

8. An electronic musical instrument comprising a plurality of tone generators, means for

60 combining the output from said generators to form a single composite signal, a tone outlet including a plurality of speakers, and means for transmitting said composite signal to the speakers comprising a high pass filter connected to said

combining means, a low pass filter connected to said combining means, a pair of substantially similar amplifiers each connected to one of said filters, a circuit interconnecting one filter and amplifier with one of said speakers, and a circuit interconnecting another filter and amplifier with another of said speakers, to give a broad frequency range output.

9. An electronic musical instrument comprising a plurality of tone generators, means for combining the output from said generators to form a single composite signal, a plurality of tone outlets including a plurality of speakers, and means for transmitting said composite signal to the speakers comprising a plurality of amplifiers, each amplifier including a pair of tubes in push-pull, and a cathode follower circuit for feeding said tubes, a high pass filter connected to said combining means, a low pass filter connected to said combining means and means respectively connecting said speakers through said amplifiers to said filters, to give a broad frequency range output.

10. An electronic musical instrument comprising a plurality of tone generators, means for combining the output from said generators to form a single composite signal, a plurality of tone outlets including a plurality of speakers, and means for transmitting said composite signal to the speakers comprising a plurality of amplifiers, each amplifier including a pair of tubes in push-pull, a phase inverter tube, and a cathode follower circuit interconnecting the phase inverter tube and push-pull tubes, a high pass filter connected to said combining means, a low pass filter connected to said combining means, and means respectively connecting said speakers through said amplifiers to said filters, to give a broad frequency range output.

11. An electronic musical instrument comprising a plurality of tone generators, means for combining the output from said generators to form a single composite signal, a tone outlet including a plurality of speakers, and means for transmitting said composite signal to the speakers comprising a pair of substantially similar amplifiers, each of said amplifiers including a pair of tubes in push-pull, and a cathode follower circuit for feeding said tubes, a high pass filter, a low pass filter, both of said filters connected to said combining means, means interconnecting one amplifier and filter with one of said speakers, and means interconnecting another amplifier and filter with another of said speakers, to give a broad frequency range output.

12. An electronic musical instrument comprising a plurality of tone generators, means for combining the output from said generators to form a single composite signal, a tone outlet including a plurality of speakers, and means for transmitting said composite signal to the speakers comprising a pair of substantially similar amplifiers, each amplifier including a pair of

tubes in push-pull, a phase inverter tube, and a cathode follower circuit interconnecting said tubes, a high pass filter, a low pass filter, both of said filters connected to said combining means, means interconnecting one amplifier and filter with one of said speakers, and means interconnecting another amplifier and filter to another of said speakers, to give a broad frequency range output.

13. An electronic musical instrument comprising a plurality of tone generators, means for combining the output from said generators to form a single composite signal, and a plurality of tone outlets each including a speaker, a selective filter, and an amplifier for transmitting said signal from said selective filter to the speaker, said amplifier including an amplifier tube, a phase inverter tube driven thereby, a pair of tubes forming a push-pull amplifier stage, a cathode follower circuit for driving said push-pull tubes, and an inverse feed back circuit for said first named amplifier tube.

14. An electronic musical instrument comprising a plurality of tone generators, means for combining the output from said generators to form a single composite signal, and a plurality of tone outlets each including a speaker, a selective filter, and an amplifier for transmitting said signal from said filter to the speaker, said amplifier including an amplifier tube, a phase inverter tube driven thereby, a pair of tubes forming a push-pull stage, and an inverse feed back circuit for the first named amplifier tube.

15. An electronic musical instrument comprising a plurality of tone generators, means for combining the output from said generators to form a composite signal, a plurality of tone outlets, and means for selectively transmitting said composite signal to said plurality of outlets comprising a signal circuit, a plurality of resistors disposed substantially in parallel with one another and arranged for connection in said circuit, means for selectively rendering said resistors operative and inoperative, and means interconnecting said resistors with said tone outlets comprising a high pass filter, a low pass filter, and an amplifier associated with each of said filters.
